UNITED STATES PATENT OFFICE.

ROBERT BEARDSLEY, OF CHICAGO, ILLINOIS.

SHADE.

Application filed July 13, 1925. Serial No. 43,293.

My invention relates to improvements in shades and particularly to lamp shades. The invention has among its other objects the production of a device of the kind described, which is extremely neat and attractive in appearance, simple, convenient and satisfactory for use wherever found applicable. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts:

20 Figure 1 is a section illustrating the manner in which I produce lamp shades embodying the invention;

Figure 2 is a fragmentary section illustrating one step in the manufacture of a 25 lamp shade embodying the invention;

Figure 3 is a fragmentary section through the improved lamp shade illustrating another step in the manufacture thereof;

Figure 4 is a fragmentary section through 30 the completed lamp shade; and

Figure 5 is a fragmentary sectional view of tools which I preferably employ in the manufacture of lamp shades embodying the invention.

35 Referring for the present to Figure 1, 10 is the body portion of a lamp shade embodying the invention, the lamp shade being shown in an intermediate stage of manufacture in this figure. The body portion 10

40 may be of any desired size and shape and may be made of any suitable material, but in this instance is shown as a frustro-conical article formed of parchmentized material which is relatively pliable. As shown in

45 Figure 4, the completed lamp shade comprises an annulus or collar 12, which is preferably formed from metal and is provided with an inwardly opening annular groove 13 adapted to accommodate an annu-

50 lar flange 14 struck up from the body portion 10. The annular flange 14 is secured in the groove 13 by a ring 15, which is preferably formed from some fibrous material, such as paper, cardboard or the like. The

55 collar 12 may be provided with screw-threads 17 or the equivalent whereby the

lamp shade may be supported by or suspended from any suitable device (not shown).

In Figures 1, 2 and 3, I have illustrated 60 various steps in the manufacture of my improved lamp shade. To assemble the lamp shade, the collar 12 is first placed upon any suitable support, such as, for instance, a plate 19, the plate 19 being provided with a recess 19^a adapted to receive the collar and a plug 20 adapted to center the collar with respect to a plurality of posts 21 projecting upwardly from the plate 19. The posts 21 are adapted to center the body portion 10 with respect to the collar 12 when the body portion is placed upon the collar in the manner illustrated in Figure 1. After the body portion 10 has been properly positioned upon the collar 12 the annular flange 14 is formed by pressing downwardly upon that part of the body portion disposed within the periphery of the collar (Figure 2). The ring 15 is then positioned upon a tool 23 70 in the manner illustrated in Figure 5, the tool 23 being provided with a cylindrical portion 24 upon which the ring 15 loosely seats. One edge of the ring 15 is then forced against a frustro-conical surface 25 formed in a block 26 to turn this inwardly in the manner illustrated in Figure 5. The tool 23 is employed to force the ring 15 into the collar 12 to secure the annular flange 14 in the groove 13. This expands the collar 12. When the tool is removed the ring 15 is 75 slightly deformed or compressed to hold the flange 14 securely in the collar 12.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. The combination with a lamp shade, of a metallic annulus having an annular groove formed in its inner surface, said shade projecting into said groove, and a second annulus expanded under pressure in said shade and engaging the groove and shade to secure it in said groove.

2. In a device of the character described, a collar having an inwardly opening annu-

lar groove, a lamp shade having an annular flange received in said groove, and an annulus expanded under pressure in said groove against said annular flange and inner wall of the groove.

3. In a device of the character described, a collar, a lamp shade having an annular flange received in said collar, an annulus expanded in said collar against said annular flange and collar, and a screw-threaded portion formed integral with said collar.

4. In a device of the character described

and in combination, an annulus formed with an inwardly opening annular groove, a lamp shade of flexible material having an annular flange received in said groove, an annulus expanded under pressure in said groove against the annular flange and inner wall of the groove, and a screw-threaded portion integral with the annulus and disposed centrally of the annular flange.

In testimony whereof, I have hereunto signed my name.

ROBERT BEARDSLEY.
